UNITED STATES PATENT OFFICE.

JOHN HUME, OF HOUSTON, TEXAS.

ENGINE-STARTER.

1,075,975.

Specification of Letters Patent.

Patented Oct. 14, 1913.

Application filed July 10, 1911. Serial No. 637,800.

To all whom it may concern:

Be it known that I, JOHN HUME, a citizen of the United States, residing at Houston, in the county of Harris and State of Texas, have invented certain new and useful Improvements in Engine-Starters, of which the following is a specification.

My invention relates to new and useful improvements in engine starters, and more particularly to such devices as are designed to be used for starting engines of the internal combustion type. The drawings illustrate the device as applied to an automobile.

The object of the invention is to provide a device of the character described so constructed as to be operated by compressed air and which may be readily connected with and disconnected from the engine so as to start the same.

20 The invention also comprehends a storage reservoir for the compressed fluid which communicates with the operative mechanism of the device and which may be filled with the motive fluid thereby and the motive fluid of which may be released therefrom so as to operate the mechanism of the device and automatically connect said operative mechanism with the engine to be started.

25 The invention further comprehends means whereby the compressed fluid may be diverted from the storage reservoir to be used for any purpose for which it may be desired to use the same, as for inflating pneumatic tires and for like purposes.

30 With the above and other objects in view the invention has particular relation to certain novel features of construction and operation an example of which will be described in this specification and illustrated 35 in the accompanying drawing, wherein:—

Figure 1, is a diagrammatic view of the complete device, Fig. 2, is a side elevation of an automobile showing the device attached thereto, Fig. 3, is a front view of an 45 automobile showing the device attached thereto, Fig. 4, is a side elevation of an internal combustion engine showing the operative mechanism of the air motor in its relation to said engine, Fig. 5, is a plan view thereof, Fig. 6, is a front elevation of said engine and motor, Fig. 7, is a plan view of the air motor, Fig. 8, is the side elevation thereof, Figs. 9 and 10 are end views, respectively, of the motor cylinders, 50 Fig. 11, shows the motor crank shaft and adjacent parts, Fig. 12, is a side elevation

of the clutch cylinder, also the clutch lever which is operated thereby, Fig. 13, is a plan view thereof, Fig. 14, is a view of the clutch shaft, in elevation, and, Figs. 15, 16 and 17, 60 are, respectively, detailed views of the valve which the air motor and the clutch cylinder may be connected with and disconnected from the storage reservoir.

Referring now more particularly to the 65 drawings, wherein like numerals of reference designate similar parts in each of the figures, the numeral 1 refers to a suitable storage reservoir which may be secured at any desired place upon the machine frame. 70 This reservoir is filled through pipes 2 and 2' through the latter of which the compressed fluid is also released from said reservoir. The pipe 2 is provided with a suitable gage 3 provided to indicate the amount of 75 fluid pressure, a safety valve 4, and a cut off valve 5 by means of which said pipe may be tightly closed and all escape from the reservoir prevented. The pipe 2' communicates with both cylinders of the air motor, 80 as shown in Fig. 7. This motor is preferably of the oscillating cylinder type and is shown in detail in Figs. 4-8 inclusive, in which the numerals 6 and 7 refer respectively, to the cylinders which are mounted 85 upon a suitable supporting frame 8 and in which the respective pistons 9 and 10 reciprocate. The pistons are connected to a crank shaft 11, in the usual manner by means of the piston connecting rods 12 and 13. In the form shown the motor is mounted 90 on the automobile frame in front of the engine and alined with the engine crank shaft 14 is the clutch shaft 15 which is rotatably mounted in suitable bearings 16, 17, 95 and 18, depending from the supporting frame of the motor. This clutch shaft also has a limited longitudinal movement in said bearings. As shown in Fig. 14 the portion of the clutch shaft which extends 100 through the bearings 16 and 17 is square and mounted thereon between the bearings 16 and 17 is a spur gear wheel 19. This gear wheel always rotates with the shaft 15 but is loosely mounted so that said shaft 105 may have free lengthwise movement relative thereto. The crank shaft 11 carries a rigidly mounted gear wheel 20 which meshes with the gear wheel 19 and transmits motion thereto and to the shaft 15 carrying the same. 110 The inner end of the shaft 15 is formed into a clutch member 21 which is arranged to en-

gage with a corresponding clutch member 22 carried by the free end of the crank shaft 14 and the outer end of said shaft 15 carries a collar 23, interposed between which and the bearing member 18 is the coil spring 24 which operates to normally hold the clutch members 21 and 22 out of engagement with each other. The outer end of shaft 15 also carries a crank 25, loosely mounted thereon and which may be clutched with said shaft by means of clutch 26, in the ordinary manner and the clutch shaft 15 then manually forced along until the clutch members 21 and 22 engage and the engine may then be manually cranked, in the ordinary manner.

The numeral 27 refers to a clutch cylinder with which the air pipe 28 communicates. This cylinder is provided with a piston 29 to the outer end of which a clutch lever 30 is hingedly attached at one end. This lever is pivotally secured to a fulcrum 31 and its other end is bifurcated, the fingers 32 and 33 thereof resting in the peripheral groove 34 of the collar 35, rigidly mounted on the shaft 15 and between the bearings 17 and 18.

When the engine is running the air motor is also forced to operate, being driven through gear wheels 19 and 20 and the air 30 is compressed thereby and driven through the pipes 2 and 2' into the reservoir L. At the same time a certain amount of air pressure is exerted through pipe 28, which communicates with pipe 2, against piston 29 and 35 said piston is thus forced out which operates through clutch lever 30 to hold shafts 14 and 15 clutched together while the reservoir is being filled. The air to be compressed is drawn into the air motor through 40 the suction pipes 36. While the reservoir is being filled the manual lever 37 will be in the position indicated by the letter C, in Fig. 1, in which position the intake 38 will be closed to pipes 2, and 2' and 28 and 45 opened to pipe 36 and the pipes 2, 2' and 28 will communicate together, all by means of valve 39, as shown more in detail in Figs. 15 and 16. The air reservoir 1 will thus be filled with compressed air through the pipes 50 2 and 2'. The lever 37 should then be moved into release position as indicated by R, in Fig. 1, in which position the pipe 2 will be closed by valve 39 and pipe 28, will be disconnected therefrom by said valve and the 55 pressure in cylinder 27 behind piston 29 being relieved the shaft 15 will be released to the operation of spring 24 and the members 21 and 22 will thereby be declutched and the motor stopped. When it is desired to 60 again start the engine the handle 37 is moved into the position indicated by the letter S, in Fig. 1, which operates through valve 39 to connect pipes 2, 36 and 28 and close them to intake 38 and to release the 65 pressure from the reservoir, through said

pipes to the air motor and the clutch cylinder 29. The pressure through pipes 2 and 36 operates to start the motor which in turn operates through gear wheels 20 and 19 to rotate the clutch shaft 15, and the pressure 70 through pipe 28 operates through piston 29 and clutch lever 30 to force the clutch members 21 and 22 into engagement and the engine is thus started. During this operation suction pipes 2' and intake 38 serve as an 75 outlet for the air from the motor. As soon as the engine starts the lever 37 is again moved into release position R, and the motor is thus stopped and clutch shaft 15 is de-clutched from engine shaft 14 in the manner 80 herein before described.

The air reservoir should be of such a size that sufficient motive fluid may be contained therein to start the engine a number of times before the pressure is entirely exhausted, 85 but when the compression has been considerably reduced in said reservoir it should be again charged in the manner herein before described.

When it is desired to use the device to inflate pneumatic tires or for similar purposes the lever 37 should be moved into the position indicated by the letter C in Fig. 1. The valve 40, controlling the pipe 41 should then be opened and the air forced by the motor through pipes 2' and 2 will be diverted from said last mentioned pipe through the pipe 41 connected therewith, and may be used for any desirable purpose.

While I have shown only one form of this 100 device I desire to reserve the right to vary the form, construction and arrangement of parts in so far as the variation thereof will not depart from the principle of the invention.

What I claim is:—

1. A device of the character described including a pressure chamber, a fluid compressor and an intake pipe therefor, a motive fluid conduit communicating with said chamber and with a motor, a mechanism operatively connected with said motor and arranged to be connected with and disconnected from the mechanism to be driven thereby, a means for forcing said mechanisms into operative connection, said means including an air cylinder, a piston reciprocating therein and a lever mounted upon a fulcrum and having one end connected to said piston and the other end connected to and actuating said first mentioned mechanism, a motive fluid conduit communicating with said first mentioned conduit and also with said air cylinder through which fluid pressure is conducted from the first mentioned conduit into said air cylinder and behind the piston reciprocating therein whereby said means is forced, by fluid pressure, to connect said driving with said driven mechanism, and a means for closing said 110 115 120 125 130

first mentioned conduit and simultaneously disconnecting the second mentioned conduit therefrom, when said means is in one position and connecting the intake with the compressor and the compressor with both of said conduits when said means is in another position.

2. A device of the character described including a pressure chamber, a fluid compressor, an intake pipe therefor, a motive fluid conduit communicating with said chamber and with said compressor, a mechanism operatively connected with said fluid compressor and arranged to be connected with and disconnected from the mechanism to be driven thereby, a means for forcing said mechanisms into operative connection, said means including an air cylinder, a piston reciprocating therein, and a lever mounted upon a fulcrum and having one end connected to said piston and the other end connected to and actuating said first mentioned mechanism, a motive fluid conduit communicating with said first mentioned conduit and also with said air cylinder, means control-

ling said conduits and arranged to admit fluid pressure from said compression chamber through said conduits to said compressor and said air cylinder simultaneously whereby said compressor is actuated and simultaneously therewith fluid pressure is admitted behind said piston reciprocating in said air cylinder, operating through said lever to connect said driving with said driven mechanism, said last mentioned means being arranged so that when moved into one position it will close the first mentioned conduit and simultaneously disconnect the second mentioned conduit therefrom and when moved into another position it will connect the intake with the compressor and the compressor with both of said conduits.

In testimony whereof I have signed my name to this specification in the presence of two subscribing witnesses.

JOHN HUME.
